A. DINKLAGE

ANCHORING DEVICE

Original Filed Aug. 16, 1922

FIG. 1.

FIG. 2.

FIG. 3.

INVENTOR

AUGUST DINKLAGE

BY
Ralph E. Layton
ATTORNEY

UNITED STATES PATENT OFFICE.

AUGUST DINKLAGE, OF EAST ORANGE, NEW JERSEY.

ANCHORING DEVICE.

Original application filed August 16, 1922, Serial No. 582,276. Divided and this application filed October 16, 1923. Serial No. 668,855.

To all whom it may concern:

Be it known that I, AUGUST DINKLAGE, a citizen of the United States, and a resident of East Orange, in the county of Essex and State of New Jersey, have invented certain new and useful Improvements in Anchoring Devices, of which the following is a specification.

This invention relates to anchoring devices 10 and has more special reference to devices for checking the creep of track rails.

The present application is a division of an application filed August 16, 1922, under Serial Number 582,276 and differs from the 15 invention disclosed in the co-pending application in that the present invention comprehends a sheet metal check element which is adapted to ultimately take a position flat against the tie, the wedging of the track rail being effected by an integral portion of the 20 check which is adapted to be swung to one side to enable the rail to be located in position and the end of which abuts against the side of the rail and is forced by the creep 25 of the rail to a wedging position.

While several types of sheet metal creep checks are known these known checks are so designed that the rail embracing portion is spaced from the tie; whereas in the present 30 invention the rail embracing portion is adapted by the creep of the rail to be driven flat against the tie which affords a substantial footing therefor and provides an effective check to the creep of the rail despite 35 the fact that the check is constructed of comparatively thin material.

While the patent to Henggi, dated January 5th, 1916, and numbered 1,167,299, discloses a rail embracing element which is 40 adapted to lie flat against the tie, this rail embracing element consists of a metal bar whereas the present invention utilizes a yieldable sheet metal check largely obviating the danger of destroying the rails, 45 which occurs quite frequently when the wheels of the rolling stock run on the rail flange instead of on the rail head and pass over the bar metal checks of Henggi. If this last named condition (the wheel leaving the rail head) should occur with the 50 check which forms the subject matter of the present invention, the result will not be disastrous to the rail since the sheet metal check will yield or bend under the wheels and not break out portions of the rail flange.

In its more specific aspect the present invention comprehends a single, substantially flat piece sheet metal check having a movable portion adapted to normally overlie the rail flange and which may be swung or bent to one side from its normal position to enable the rail to be seated within the check. When this movable portion is partly restored to its normal position overlying the rail flange, the latter is encompassed by the 60 check and a separation of the two is prevented. While the movable portion serves as a rail encompassing extension or closing piece, as indicated, nevertheless the movable portion is adapted to perform an additional 65 function, namely, to wedge the check to the rail, and this may be and preferably is achieved by dimensioning the movable portion so that the radius of rotation of the movable portion is greater than the distance 70 from the axis of rotation to the rail, the effect being that when the movable portion or flap is initially driven toward its normal position, the end of the flap abuts tightly against the side of the rail and quite effectively prevents creep of the rail. In order to increase the effectiveness of the check, the flap may be and preferably is positioned at an angle to the rail with its forward end 75 thrusting against the rail, so that the tendency of the creep of the rail is to carry the flap about its axis toward the point of the shortest distance between the rail and the axis of rotation of the flap.

While one embodiment of the invention is 80 disclosed in the drawing, it is to be understood that this embodiment merely serves as an illustration of the underlying principles of the invention, so that they may be readily comprehended by those skilled in the art and 85 are not intended as limiting the invention to the specific forms disclosed therein.

In said drawing:

Fig. 1 is a front elevation of the invention.

Fig. 2 is a front elevation of the invention 100 applied to the rail, and

Fig. 3 is a top plan view of the embodiment shown in Figs. 1 and 2, the check being shown as initially positioned.

Continuing now by way of a more detailed description, a check indicated in its entirety by A may and preferably does consist of a single sheet of metal comprehending an upstanding portion or wing B preferably provided with an indent or rail receiving re- 105

cess B', the latter preferably having a configuration corresponding in general to the cross-sectional configuration of the rail flange so that one side of the rail is preferably held in a comparatively immovable position.

Inasmuch as the check preferably consists of comparatively thin material, in general the upstanding portion B will be carried up a considerable distance so that sufficient strength of material is provided to withstand the lateral thrust of the wedging action of the check. A similar upstanding wing C is located in spaced relation to the wing B and has a rail receiving recess C' preferably shaped to conform to the rail edge. In order that the rail flange may be located in the check, one or both of the upstanding wings may be slit as at D to permit the wing to be bent to one side for instance along the vertical dotted line indicated in Figs. 1 and 2, which may then be considered as the axis of rotation of the wing or flap. In order to afford the desired wedging action of the check against the rail, the distance between the fixed edge E and the movable edge F is normally less than the width of the rail flange with which the check is designed to cooperate. On driving the flap toward its normal position, the movable edge F strikes the rail flange edge and locks the check and rail together. Creep of the track rail not only tends to further rotate the flap or wing about its axis but also forces the entire check to approximately a flat position against the tie, a substantial footing being thereby provided for the check and effectively preventing creep. A laterally projecting tab G may be and preferably is utilized to steady the check until the creep of the rail has driven it firmly against the tie and this tab will serve to assist in retaining the check in place even after a complete wedging action has taken place.

While various equivalents and equivalent modifications are mentioned in the foregoing specification, it is to be understood that these are not the only equivalents which may be used and are only inserted for the purpose of affording a clear understanding of the principles of the invention and are in no wise intended to limit its scope.

It is claimed:

1. A creep check having one portion held relatively stationary to a rail and having a movable rail engaging part adapted to engage one side of the rail and to be rotated relatively thereto by the creep of the track rail, the check being adapted to take a position flat against a tie.

2. A creep check having oppositely disposed parts adapted to engage opposite sides of a rail, the distance between the parts being variable and the creep of the rail decreasing the distance between said parts.

3. A creep check having a portion adapted to engage one side of a rail and a second portion oppositely disposed to the first mentioned portion, the last mentioned portion being adapted to be swung to one side to permit the rail to be located in the check and to engage one side of the track rail. 70

4. A creep check having a portion adapted to engage one side of a rail and a second portion oppositely disposed to the first mentioned portion, the last mentioned portion being adapted to be swung to one side to permit the rail to be located in the check; the creep of the rail locking the movable portion to the rail. 75

5. A flat creep check element having a portion movable relatively to the plane of the element by the creep of the rail, the element being adapted to lie flat against a tie. 80

6. A flat sheet metal creep check element having a portion movable about an axis which is perpendicular to the plane of the rail base. 85

7. A creep check element having a movable rail engaging portion, said portion being adapted to move relatively to the plane of the element by the creeping of the rail and more firmly lock the check to the rail; the element being adapted to lie flat against a tie. 90

8. A sheet metal creep check element having a movable portion, the movable portion having a rail receiving recess, the check element being adapted to take a position flat against a tie. 100

9. A creep check element having a portion slit to provide a movable portion having a rail receiving recess.

10. A sheet metal creep check having rail engaging portions, one of which is movable, on opposite ends and adapted to lie flat against a tie when in wedging position. 105

11. A creep check element adapted to lie flat against a tie and having a relatively movable wedging means to lock the check to the rail. 110

12. A creep check comprising a rail embracing member adapted to lie flat against a tie and having portions adapted to engage opposite sides of the rail, the distance between the portions being variable. 115

13. A creep check comprising a rail embracing member adapted to lie flat against a tie and having portions adapted to engage opposite sides of the rail, the distance between the portions being variable. 120

14. A creep check element having portions adapted to engage opposite sides of the rail, the distance between the portions being decreaseable to less than the width of the rail when the check is not in use. 125

15. A flat sheet metal creep check having a rail receiving recess and having a wing arranged above the recess which may be moved to permit the rail to be located in the

- check and which encompasses the rail flange when restored to its normal position, the wing being moved to a wedging position by the creep of the rail.
- 5 16. A sheet metal check having a flap projecting at an angle to the plane of the body of the check, the forward edge of the flap being adapted to receive and bear against a rail flange.
- 10 17. A creep check comprising oppositely disposed upstanding wings, one of said wings being slit to permit a portion of the wing to be swung to one side to permit the rail to be located between the wings, a portion of the swinging part of the wing abutting against the rail and locking the check to the rail.
- 15
18. A creep check comprising oppositely disposed upstanding portions, one portion being slit to permit this portion to be swung from its position, an edge of the portion being adapted to engage the rail edge and the creep of the rail swinging the portion back to its normal position and tightening the check on the rail. 20
19. A creep check comprising a movable portion adapted to overlie the rail to prevent separation of the check from the rail to abut against the rail edge, and to wedge the check to the rail. 25
- 30

Signed at the city of New York, in the county of New York, and State of New York, this 10th day of October, 1923.

AUGUST DINKLAGE.
